UNITED STATES PATENT OFFICE

1,993,173

VENETIAN BLIND CONSTRUCTION

Peter H. Kuyper, Pella, Iowa, assignor to
 Rolscreen Company, Pella, Iowa, a corporation
 of Iowa

Original application January 15, 1934, Serial No.
 706,631. Divided and this application March
 12, 1934, Serial No. 715,148

14 Claims. (Cl. 156—17)

The object of my invention is to provide a venetian blind construction which is simple, durable and comparatively inexpensive to manufacture, the present application being a division of my 5 copending application Serial No. 706,631, filed January 15th, 1934, patented May 1, 1934, No. 1,957,272.

A further object is to provide a venetian blind construction in which a casing is removably associated with a window frame and supports a venetian blind as well as its raising and tilting or adjusting mechanism so that the casing can be readily removed for the purpose of cleaning or painting the blind, or cleaning, repairing or oiling the operating mechanism for the blind, the removable feature also being desirable so that blinds of different characteristics or color designs can be interchanged readily at will.

Still a further object is to provide casings which 20 may be supplied by the manufacturer in successive lengths, for instance in one inch steps, and to provide supporting brackets of different sizes to compensate for fractions of an inch, whereby a blind of one length may accommodate window 25 frame widths of any range within a quarter and an inch and a quarter greater than the length of the venetian blind casing itself, thus facilitating installation and keeping the dealer's stock on hand to a minimum.

Still a further object is to provide a venetian blind having a novel tipping mechanism comprising a pair of rotatable elements with the straps of a tape ladder wound thereon, one clockwise and the other counterclockwise, the tipping or 35 adjusting control comprising means for simultaneously rotating the rotatable elements in the same direction so that one strap winds up while the other one unwinds.

Still a further object is to arrange the straps 40 so that the speed of the one which winds up increases with respect to the speed of the one which unwinds so that the blind slats will be shifted toward the window when adjusting the slats to closed position, resulting in better closure 45 of the slats with respect to the window and also with respect to each other, the latter result being due to the slats in their finally adjusted position and the entire venetian blind itself being supported on one strap only.

A further object is to provide raising means for the venetian blind having a novel locking arrangement to prevent lowering of the blind, the lock being in the form of a cam, a manual control being provided for the cam to lock it and it

being movable to unlocked position by a slight raising of the blind.

A further object is to provide novel characteristics such as latches for the casing with respect to the brackets which support it, pulley arrangements for the raising ropes, a brake for the rotatable elements, a disconnecting means between the tape ladders and the supporting casing and the like.

With these and other objects in view my invention consists in the construction, arrangement and combination of the various parts of my device, whereby the objects contemplated are attained, as hereinafter more fully set forth, pointed out in my claims, and illustrated in the accompanying drawings, in which:

Figure 1 is an inside elevation of a venetian blind structure embodying my invention.

Figure 2 is a plan view of the same on the indicating line 2—2 of Figure 1.

Figure 3 is a view similar to the right hand end of Figure 2 illustrating a different adjustment of the blind mechanism casing with respect to its supporting bracket.

Figure 4 is a similar view showing a different 25 bracket.

Figure 5 is an enlarged sectional view on the line 5—5 of Figure 2.

Figure 6 is an enlarged plan view of the right hand end of Figure 2 showing part of the structure broken away and in section.

Figure 7 is a sectional view on the line 7—7 of Figure 2.

Figure 8 is a sectional view on the line 8—8 of Figure 6 showing a locking arrangement for the 35 blind raising mechanism.

Figure 9 is a sectional view on the line 9—9 of Figure 6.

Figure 10 is an enlarged sectional view on the line 10—10 of Figure 2 showing an adjusting 40 drum.

Figure 11 is an enlarged sectional view on the line 11—11 of Figure 1 showing the tape ladder supporting and adjusting mechanism.

Figure 12 is a detailed sectional view on the line 45 12—12 of Figure 11 showing a connection between one of the straps of the tape ladder and a rotatable element on which it is wound; and

Figure 13 is a perspective view of a connecting device between the supporting casing and the 50 tape ladders of the venetian blind.

On the accompanying drawings, I have used the reference numeral 10 to indicate the side jamb of a window frame. The head jamb thereof is indicated at 12. Brackets A are adapted for sup- 55

port with respect to the window frame and in turn support a venetian blind mechanism casing B.

The casing B comprises a bottom wall 14, a back 5 or outer wall 16 and a front or inner wall 18. Within the casing 18, rotatable elements 20 and 22, such as rods or shafts, are journaled in transverse brackets 24 and 26. Each rotatable element 20 and 22 has thereon a pinion 28.

10 The pinions 28 mesh with a pinion 30 which is non-rotatably associated with a drum 32. A cord or other flexible element 34 has its center secured as by a cotter key 36 to the drum 32. The ends of the cord 34 depend from the drum after passing through a slot 35 and over a roller 37 and are provided on their lower ends with knobs 52. The knobs 52 are preferably of metal or other heavy material to maintain the cords taut and also to indicate by their comparative elevations which 15 end of the cord is to be pulled downwardly in order to adjust the slats of the venetian blind as desired.

The rods 20 and 22 may have a tendency to rotate too freely and to counteract this tendency I 25 provide a brake means in the form of a strip of metal or the like 38 frictionally engaging the rotatable elements. To adjust the frictional effect of the strip 38, I provide a bolt 40 which can be tightened to increase the friction or loosened 30 to decrease it in an obvious manner.

Wound on the rod 20 is a pair of doubled tapes 42 while wound on the rod 22 in an opposite direction is a pair of doubled tapes 44. The tapes 42 and 44 are adapted to support straps 54 of a tape ladder, the rungs of which are indicated at 55.

The tapes 42 and 44 are connected with looped upper ends of the straps 54 by fasteners 46, such as shown in Figure 13, which can be inserted in 40 the looped upper ends of the straps and through the looped tapes 42 and 44 and then fastened together by adjustment to the dotted line position of Figure 13 as indicated by the arrow a.

The particular arrangement of the doubled 45 straps 42 and 44 (which however can be single with looped ends if desired) accomplishes a very desirable result, especially when associated with the adjusting rods 20 and 22 as disclosed. When the slats 58 are adjusted to their closed position 50 as shown in Figure 11, the rod 22 is unwound and the rod 20 is wound, both at the same speed. The diameter of the tape 44 on the rod 22, however, decreases, while the diameter of the tape 42 on the rod 20 increases so that in the final position, 55 the right hand strap 54 only is supported and supports the other strap 54, the rungs 55, the slats 56 and the ropes 60. This places the slats 56 in the closest possible overlapping position—that is, as close as the ropes 60 between them will 60 permit, as is obvious by a minute inspection of Figure 11.

Furthermore, it will be noted that the entire blind is supported under the rod 20 rather than in a central position below the rods 20 and 22, thus 65 placing the slats 56 as near as possible to the portion 11 of the window frame, which portion is usually in the form of a flange surrounding the window itself, the numeral 13 indicating a similar flange at the head of the window.

70 The tapes 42 and 44 themselves are secured to the rods 20 and 22 by pins 50 (see Figure 12) drawn into slots 48 formed in the rods.

The venetian blind itself includes a plurality of slats 56 made of wood or the like in the ordinary manner and having slots 58 for raising ropes 60

to extend through. The lower slat, indicated at 57, I prefer to make of metal so that it has the same thickness as the lighter slats 56, yet has greater weight so as to keep the blind in taut position when it is lowered without providing an unsightly much thicker bar as would be necessary when making it of wood.

5 The ropes 60 have their lower ends secured to the metal slats 57 as at 57a and extend upwardly through the slots 58 of the successive slats 56. 10 The ropes then extend over pulleys 62 and then around pulleys 64 and 66.

The pulleys 64 and 66 are housed in a channel-shaped bracket 68 in which is also journaled a pulley 70. The ropes 60 extend over the pulley 15 70 and then downwardly through an opening 71 in the bottom 14 of the casing B.

A pulley 72 is provided under which the ropes 60 may be swung outwardly from the window frame when raising the venetian blind without 20 unduly chafing the ropes or causing them to jump off the pulley 70. The right hand bracket 26 is provided with a notch 61 for one of the ropes to extend through before it reaches the pulley 66.

I provide a novel locking means for the raising 25 ropes 60 in the form of a cam 74 pivoted at 76 (see Figure 8) and having an arm 75 extended through a notch 77. The blind can be adjusted by the ropes 60 to any desired position and a rope 78 attached to the arm 75 may then be pulled 30 downwardly to swing the locking cam to its dotted line position, thereby forcing its upper end against the ropes 60 and confining the ropes between the cam and locking grooves 79 formed in the bracket 68. The ropes 60 may then be released and the 35 weight of the blind will tend to keep the cam 74 engaged.

Subsequently, whenever it is desired to either raise or lower the blind, the ropes 60 may be pulled which will unlock the cam and may then 40 be further pulled for raising the blind or slackened to lower it.

On the locking rope 78, I provide a weighted 45 knob 80, while on the ropes 60 I provide a rectangular buckle-like element 82 having a cross bar so that the ropes 60 may be adjusted relative thereto to facilitate equal draft on the ropes 60 when raising the blind and thereby keeping its lower end level.

The brackets A comprise webs 84 which may be 50 secured by screws or the like to the side jambs 10 or may be secured to the head jamb 12 if desired adjacent its ends. Each bracket A has a supporting flange 86 on which the ends of the casing B rest. A back flange 88 is provided to limit outward movement of the casing B when it is inserted past inner flanges 90. The flanges 90 are provided for spring latches 92 to snap behind when the casing is in supported position.

Finger engaging portions 94 are provided on 60 the latches 92 which can be pulled toward each other when it is desired to remove the casing B from its supported position on the flanges 86.

In Figure 2, the casing B is shown supported between side jambs 10 which are as close together 65 as this length of casing will permit and yet allow room between the ends of the front wall 18 and the flanges 90 for the latches 92 to pass when installing or removing the casing B.

In Figure 3, I have shown the same bracket A 70 in a window frame of slightly greater width. The spring latches 92 take up the difference and close the space between the flanges 90 and the ends of the front wall 18 as clearly shown. Also the resiliency of the latches 92 tends to center the 75

casing B with respect to the brackets A supporting its ends.

In Figure 4, I have shown the same casing B installed in a still wider window frame, a bracket 5 A' being provided in this case. It is similar to the bracket A except that the flanges indicated at 86a, 88a and 90a are wider. Thus it will be obvious that a range of dimensions over an inch or so can be taken care of by a casing of one 10 length and brackets of different sizes.

When interchanging, cleaning, painting, oiling or the like, it will be obvious that my construction facilitates any of the operations mentioned. The casing and therefore the entire 15 blind structure is removable from the supporting brackets A and can be placed on a work bench where the parts of the blind are much easier to get at than when trying to perform any operations on them while in installed position.

20 The various features disclosed go to make up a very efficiently operable blind and one which has many novel features.

Some changes may be made in the construction and arrangement of the parts of my device 25 without departing from the real spirit and purpose of my invention, and it is my intention to cover by my claims, any modified forms of structure or use of mechanical equivalents, which may be reasonably included within their scope.

30 I claim as my invention:

1. In a venetian blind structure having a casing for supporting a venetian blind, raising means and adjusting means therefor also supported by said casing, brackets for attachment to a window 35 frame, said casing having its ends resting on but not secured to said brackets and latches to normally retain said casing in supported position on said brackets.

2. In a venetian blind structure having a casing 40 for supporting a venetian blind, raising means and adjusting means therefor also supported by said casing, brackets, one for attachment adjacent each end of the head jamb of a window frame, each bracket having a flange to support 45 one end of said casing and a second flange inward with respect to said window frame and a spring latch on each end of said casing to snap behind said respective second flanges to retain said casing in supported position.

50 3. In a venetian blind structure, a raising rope and means for retaining said rope in adjusted position comprising a stationary bracket through which the rope extends and a cam pivoted therein and engageable with the rope to squeeze it 55 between the bracket and the cam.

4. In a venetian blind structure, a raising rope and means for retaining said rope in adjusted position comprising a stationary bracket through which the rope extends, a cam pivoted therein 60 and engageable with the rope to squeeze it between the bracket and the cam and independent means for moving said cam to locking position.

5. In a venetian blind structure, a casing supporting a venetian blind and its operating and 65 adjusting mechanism, brackets for attachment, one adjacent each end of a head jamb, means on said brackets to support the ends of said casing and to limit its position toward a window in a window frame including said head jamb 70 and means carried by said casing to retain it in supported position on said brackets.

6. In a venetian blind structure for a casing having a venetian blind, raising means and adjusting means therefor, all three supported by said casing, brackets for attachment to a window frame, said casing having its ends resting on but not secured to said brackets and quickly actuatable means for normally retaining said ends with respect to said brackets.

7. A venetian blind comprising a support in the form of a housing having means carried thereby and concealed therein for suspending a venetian blind therefrom, brackets, one for attachment adjacent each end of the head jamb of a window frame and a spring latch on each end of said housing to snap behind portions of 10 said brackets to retain said housing in supported position thereon.

8. A venetian blind comprising a support in the form of a housing having means carried thereby and concealed therein for suspending a 20 venetian blind therefrom, brackets, one for attachment adjacent each end of the head jamb of a window frame and spring latch means causing coaction between the ends of said housing and said brackets to retain the housing in supported 25 position with relation to the brackets.

9. In a venetian blind structure, a raising rope and means for retaining said rope in adjusted position comprising a stationary bracket through which the rope extends, a cam pivoted therein 30 and engageable with the rope to squeeze it between the bracket and the cam, said cam being normally released and means for moving said cam to locking position.

10. A venetian blind comprising a support in 35 the form of a housing having means carried thereby and concealed therein for suspending a venetian blind therefrom and for tilting said blind and means for applying yielding tension on said first means to resist tilting.

11. A venetian blind comprising a support in the form of a housing having means carried thereby and concealed therein for suspending a venetian blind therefrom and for tilting said blind and means operable from the exterior of 45 said housing for applying yielding tension on said first means to resist tilting.

12. A venetian blind comprising a support in the form of a housing having means carried thereby and concealed therein for suspending a 50 venetian blind therefrom, a raising rope and means for retaining said rope in adjusted position, said last means being supported by said housing and concealed therein.

13. A venetian blind comprising a support in 55 the form of a housing having means carried thereby and concealed therein for suspending and tilting a venetian blind, a raising rope, and means for retaining such rope in adjusted position, said last means being supported by said housing and 60 concealed therein.

14. A venetian blind comprising a support in the form of a housing having rotary means mounted wholly therewithin and concealed thereby for tilting a venetian blind suspended therefrom, a raising rope, and means for retaining said rope in adjusted position, said last means being mounted wholly within said housing and concealed thereby.

DISCLAIMER

1,993,173.—*Peter H. Kuypers*, Pella, Iowa. VENETIAN BLIND CONSTRUCTION. Patent dated March 5, 1935. Disclaimer filed October 28, 1938, by the assignee, *Rolscreen Company*.

Hereby enters this disclaimer to claims 1, 6, 12, 13, and 14 of said specification.
